UNITED STATES PATENT OFFICE.

JOHN DEMETER, OF STRATTON, ONTARIO, CANADA.

RAILWAY-RAIL JOINT.

1,391,465.

Specification of Letters Patent. Patented Sept. 20, 1921.

Application filed June 11, 1921. Serial No. 476,849.

To all whom it may concern:

Be it known that I, JOHN DEMETER, a citizen of the Dominion of Canada, residing at Stratton, in the district of Rainy River and Province of Ontario, Canada, have invented certain new and useful Improvements in Railway-Rail Joints, of which the following is a specification.

The present invention relates to improvements in rail joints. The principal object is to provide a joint which is efficient in use, economical to manufacture and which may be readily positioned or dismantled.

A further object is to provide a joint which will hold the bolts of the same in position if any of them should break.

With these and other objects in view, the invention consists in the construction, combination and arrangement of parts as will be hereinafter fully described, illustrated in the accompanying drawings and pointed out in the claims hereunto appended.

Figure 1 is a perspective view illustrating the embodiment of my present invention.

Fig. 2 is a top plan view of the same.

Fig. 3 is a side elevation illustrating the locking members in disengaged position.

Fig. 4 is a cross section on line 4-4 of Fig. 2.

Fig. 5 is a perspective view of the locks functioned to hold the locking members in engaged position.

Fig. 6 is a perspective view of one of the bolts embodied in my present invention.

Figs. 7 and 8 are perspective views, further illustrating the locking construction of Fig. 5.

Referring to the drawings, like numerals designate like parts in the various drawings.

The numerals 9 and 10 indicate the ends of the rails to be connected, 11 and 12 the fish plates constructed as indicated diagrammatically and having the hinged locking members 13, 14, 15 and 16 hingedly mounted members 13, 14, 15 and 16 hingedly mounted by means of the rivets 17, 18, 19 and 20, substantially positioned in the fish plates and having their outer ends enlarged. The ends of the fish plates are arcuate as indicated by the numeral 21 to allow free movement of the same. The numeral 22 indicates the bolts, or pins, as they will be now termed, which are positioned as indicated diagrammatically in Fig. 2. These pins are seated in the fish plates, the ends 23 being tapered and having lugs 24 configurated thereon, adapted to be seated in corresponding open-

ings 25 in the fish plates, as clearly indicated in Fig. 3. In each end of the rail, two of these pins are positioned, as indicated diagrammatically. Openings 26 are positioned in the hinge members 13, 14, 15 and 16 for reception of the outer ends 27 of the pins 22. A portion from each side of the pin is removed, making the corresponding sides of the same parallel for engagement with the parallel sides of the openings 26.

When in position, it is obvious that the abutment 28 will bear against the face of the hinged members 13, 14, 15 and 16 and prevent displacement of the pins 22. To keep the hinge members in engaged position, locking mechanism, which will now be described, is embodied. Intermediate the inner ends of the hinged members, a portion indicated by the numeral 29 is configurated on a fish plate and its sides slanted to allow free disengagement of the hinge members.

An aperture 32 is positioned in the end of each hinge member for reception of the slideable pins 33. These pins are urged outwardly by the coil springs shown in dotted lines and indicated by the numeral 34. The outer faces 35 of the pins 33 are angular to permit the hinged members 13, 14, 15 and 16 to readily engage with the same. A handle 36 is connected to each of the slideable pins 33 and slides in the longitudinal openings 37. The outer edges of the device will also be secured to the ties by means of spikes 38.

While I have illustrated and described the preferred form of construction of my invention, this is capable of variation and modification without departing from the spirit of the invention. I, therefore, do not wish to be limited to the precise details of construction specified, but desire to avail myself of such variations and modifications as come within the scope of the appended claims.

From the foregoing, it is thought that the construction of my invention will be clearly understood and therefore, a more extended explanation has been omitted.

What I claim as new is:

1. A means for connecting rails, said means comprising fish plates positioned oppositely on each side of the said rails, pins through the said fish plates and said rails, an enlarged head on each of the said pins, a lug projecting from the said head and engaging with an opening configurated in one of the fish plates, the said enlarged head and

projecting lug adapted to prevent displacement of the said pins, portions removed from the opposite sides of the said pins, the said hingedly mounted members adapted to engage with the said pins and to secure the said pins in position.

2. A means for connecting rails, said means comprising fish plates positioned oppositely on each side of the said rails, pins through the said fish plates and said rails, an enlarged head on each of the said pins, a lug projecting from the said head and engaging with an opening configurated in one of the fish plates, the said enlarged head and projecting lug adapted to prevent displacement of the said pins, portions removed from the opposite sides of the said pins, the said hingedly mounted members adapted to engage with the said pins and to secure the said pins in position and means securing the said hingedly mounted members in locked position.
3. A means for connecting rails, said means comprising fish plates positioned oppositely on each side of the said rails, pins

through the said fish plates and said rails, an enlarged head on each of the said pins, a lug projecting from the said head and engaging with an opening configurated in one of the fish plates, the said enlarged head and projecting lug adapted to prevent displacement of the said pins, portions removed from the opposite sides of the said pins, the said hingedly mounted members adapted to engage with the said pins and to secure the said pins in position, said means comprising a portion configurated on the said fish plates intermediate the inner ends of the said hingedly mounted members, pins slidably positioned in the said portion for engagement with apertures positioned in the inner ends of the said hingedly mounted members.

In testimony whereof I affix my signature in the presence of two witnesses.

JOHN DEMETER.

Witnesses:

J. A. WALLACE,
W. H. ELLIOTT.
